Application January 2, 1948, Serial No. 160

9 Claims. (Cl. 229—31)

1

This invention relates to improvements in display boxes or cartons and particularly to a display box or carton formed from a single blank of card or paper board material.

Display boxes or cartons of the type having a supporting display base with a hinged cover or lid are quite old but in the past have been formed of set-up construction requiring a relatively large amount of storage space as well as making large and bulky packages for shipment to the user. By the present invention there is provided a display box or carton that can be shipped to the user in a knocked-down condition thereby reducing shipping bulk and storage space to but a fraction of what was heretofore required.

It is therefore the principal object of the present invention to provide a display box, carton or package formed from a single blank that can be shipped to the user in a knocked-down condition.

Another object of this invention is the provision of a knocked-down display box or carton that upon erection has strength and rigidity favorably comparable with the set-up display boxes or cartons heretofore employed.

Another object of the present invention is the provision of a display box or carton of a knocked-down construction that lends itself to economical production thereby enabling the use of such a box or carton with items that will not normally afford the utilization of the more expensive set-up boxes or cartons of comparable nature and function.

It is also an object of this invention to provide a display box or carton capable of modification enabling the adaptation thereof to goods or items which could not be adapted to the set-up boxes due to constructional features and economic reasons as pointed out above.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a plan view of a blank showing the same partly assembled from which the display box or carton of the present invention is formed.

Fig. 2 is a transverse sectional view through the blank of Fig. 1 in its knocked-down condition and as shipped to the user.

2

Fig. 3 is a perspective sectional view through an erected carton.

Fig. 4 is a fragmentary sectional view taken at right angles to Fig. 3 on line 4—4 on said Fig. 3 and assuming the lid or cover is closed.

Fig. 5 is an extended plan view of a half blank showing a modification over that of Fig. 1 but presenting substantially a similar appearance as the construction of Fig. 1 when erected and placed in use.

Fig. 6 is a transverse sectional view of the blank of Fig. 5 in its knocked-down condition and as shipped to the user.

Fig. 7 is a perspective sectional view of an erected carton formed from the blank of Fig. 5.

Fig. 8 is a fragmentary sectional view taken at right angles to Fig. 7 on line 8—8 on said Fig. 7.

Fig. 9 is a plan view of a half blank showing a further modification of the invention with a portion of the blank of Fig. 9 folded or partially erected.

Fig. 10 is a transverse sectional view of the blank of Fig. 9 in its knocked-down condition and as shipped to the user.

Fig. 11 is a perspective sectional view through an erected display box or carton formed from the blank of Fig. 9.

Fig. 12 is a fragmentary sectional view taken at right angles to that of Fig. 11 on line 12—12 on said Fig. 11 and assuming that the lid or cover of the box or carton is closed.

Fig. 13 is a plan view of a half blank showing a further modification therein and in which a stop within the lid is provided cooperating with the base in closing the display box or carton.

Fig. 14 is a transverse sectional view of the blank of Fig. 13 showing the same in its knocked-down condition and as shipped to the user.

Fig. 15 is a perspective sectional view of an erected carton formed from the blank of Fig. 13.

Fig. 16 is a fragmentary sectional view taken at right angles to Fig. 15 on line 16—16 on said Fig. 15 and assuming that the lid or cover is closed.

Fig. 17 is a fragmentary view partly in section and partly in elevation as seen from line 17—17 on Fig. 16.

Fig. 18 is a fragmentary sectional view taken at right angles to Fig. 17 on line 18—18 on said Fig. 17.

Fig. 19 is a plan view of a further modification illustrating particularly a modification in the end walls of the box or carton with said plan view having a portion of the blank folded to its final shipping position.

Fig. 20 is a transverse sectional view of the

blank of Fig. 19 in its knocked-down condition and as shipped to the user.

Fig. 21 is a perspective sectional view of an erected carton from the blank of Fig. 19.

Fig. 22 is a fragmentary sectional view taken at right angles to Fig. 21 on line 22—22 on said Fig. 21.

Fig. 23 is an end elevational view of an erected carton or display box formed from the blank of Fig. 19.

Fig. 24 is a plan view of a blank modified over that of Fig. 19 with a portion thereof folded to its final knocked-down position.

Fig. 25 is a transverse sectional view through the blank of Fig. 24 showing same in its knocked-down condition and as shipped to the user.

Fig. 26 is a perspective sectional view of an erected display box or carton formed from the blank of Fig. 24.

Fig. 27 is a sectional view taken at right angles to Fig. 26 on line 27—27 of said Fig. 26.

Fig. 28 is an end view of an assembled or erected display box or carton formed from the blank of Fig. 24.

Fig. 29 is a plan view of a blank modified over that shown in Fig. 24 with a portion thereof folded to its final knocked-down position.

Fig. 30 is a transverse sectional view through the folded or knocked-down blank of Fig. 29 in the condition as shipped to the user.

Fig. 31 is a perspective sectional view of an erected carton from the blank of Fig. 29 as seen from the rear or cover side of the carton.

Fig. 32 is a sectional perspective view, similar to Fig. 31, as seen from the front or display base side of the carton.

Fig. 33 is a fragmentary sectional view through the carton, and assuming the cover or lid is closed, as seen from line 33—33 on Fig. 31.

Fig. 34 is an end elevational view of a carton as erected from the blank of Fig. 29.

Fig. 35 is a plan view of a blank modified over that disclosed in Fig. 19 with a portion thereof folded to its final knocked-down position.

Fig. 36 is a transverse sectional view through the knocked-down blank of Fig. 35 in the condition as shipped to the user.

Fig. 37 is a sectional perspective view of an erected carton formed from the blank of Fig. 35 as seen from the rear or cover side thereof.

Fig. 38 is a perspective sectional view, similar to Fig. 37, as seen from the front or display base side thereof.

Fig. 39 is a fragmentary sectional view taken at right angles to Fig. 37, and assuming that the cover or lid is closed, as seen from line 39—39 on said Fig. 37.

Fig. 40 is an end elevational view of an erected carton from the blank of Fig. 35.

Throughout the several views of the drawings similar reference characters are employed to denote the same or similar parts.

As was pointed out above this invention relates to improvements in a display box or carton formed from a knocked-down blank to be assembled by the user upon desiring to place merchandise therein for shipment and display. As pointed out above various modifications of the invention are disclosed each including the basic or underlying elements of the display box or carton of the present invention which includes a base member of appreciable thickness thereby providing a display bed together with a cover or lid integrally and hingedly connected with the base together with cooperating means on

said base and said cover or lid for limiting the closing of the cover or lid.

In the following specific description of the several modifications only the specific differences between the blanks and cartons over those disclosed in Figs. 1 to 4, inclusive, will be pointed out.

Specifically, and referring to Figs. 1 to 4, inclusive, the blank comprises a main or base supporting panel 30 bounded by cut lines 31 and 32 at opposite sides thereof and score or fold lines 33 and 34 at the remaining opposite sides of said bottom supporting panel. The score or fold lines 33 and 34 may be considered as the back and front of said panel since they are of greater length than the remaining cut sides 31 and 32 and are respectively remote and near to the observer. It is to be understood however that this nomenclature is used merely for the purpose of description. The blank has integrally hingedly connected to the main or base supporting panel 30 through the score or fold line 34 an extension 35 which will fold to form the supporting base for the goods or article to be shipped and displayed in the carton of the present invention.

The extension 35 comprises a main or goods supporting panel 36 of a length substantially equal to the length of the bottom or base supporting panel 30 but of a width slightly less than the width of the said panel 30 for providing a flange as will presently be made clear. The goods supporting panel 36 is bounded by score or fold lines 37, 38, 39 and 40. Between the score or fold lines 34 and 38 are panels 41 and 42 separated from one another by a score or fold line 43.

Attached to the opposite ends of the goods supporting panel 36, through the score or fold lines 37 and 39, are similar flaps 44 each longitudinally divided by a score or fold line 45 to form in the said flaps panels 46 and 47.

The goods supporting panel 36 has hingedly connected thereto, through the score or fold line 40, a panel 48 of a width substantially equal to the width of panel 42 and serves the same purpose thereof as will later be made clear. The panel 48 has its other side defined by a score or fold line 49 for hingedly connecting therewith a glue flap or panel 50.

The panels 42 and 48 each has its opposite ends defined by a score or fold line 51 and 52 for, respectively, hingedly connecting to the ends of the panel 42 tucking flaps or ears 53 and to the ends of the panel 48 similar tucking flaps or ears 54. The ends of the glue flap or panel 50 are partially defined by score or fold lines 55 for integrally, hingedly connecting to the ends of said panel 50 tucking flaps 56. The glue flap or panel 50 has the balance of its ends defined by cut lines 73' which are inset from the score or fold lines 55 to form locking shoulders as will presently be made clear.

The blank has integrally hingedly connected to its bottom or base supporting panel, through the score or fold line 33, a panel 57 whose other side is defined by a score or fold line 58 for hingedly connecting therewith the lid or cover panel 59.

The lid or cover panel 59 has its remaining sides defined by score or fold lines 60, 61 and 62. The score or fold line 61 hingedly connecting to the lid or cover panel 59 an extension 63' that forms the cover front wall and which extension is divided by a plurality of score or fold lines 62', 63 and 64 to form in said extension, between the score or fold line 61 and the free edge thereof,

panels 65, 66, 67 and 68. The panel 65, in the erected carton forms the cover front wall outer wall member, has its opposite ends defined by score or fold lines 69 through which there is hingedly connected with the said panel ends corner pieces 70 which, as will later be made clear, form, well known in the trade, bellows corners. The panel 66, in the erected carton forms the cover front wall bottom wall member, has its ends defined by cut lines 71 while the panel 67, in the erected carton forms the cover front wall inner wall member, has its ends in part defined by score or fold lines 72 and in part by cut lines 73 which are inset from the score or fold lines 72 thereby providing a shoulder 74 for a purpose later to be made clear. The panel 67 through its end scores 72 has hingedly connected thereto flaps 75 which are adapted to be tucked within the end walls to be enfolded thereby.

The cover panel 59 through its end score or fold lines 60 and 62 has integrally, hingedly connected therewith similar extensions 76 which in the erected carton form the cover end walls and it is deemed sufficient if but one of said extensions be described in detail. Accordingly, the extension 76 is provided with a pair of score or fold lines 77 and 78 thereby providing in the extension between the score or fold line 60 and the end of the extension, panels 79, 80 and 81. The panel 79, in the erected carton forms the end wall outer wall member and has its ends defined by score or fold lines 82 and 83 through the former of which is integrally hingedly connected thereto the corner piece 70. The panel 79 has connected to its other end through the score or fold line 83 a corner piece 84 which is substantially identical with the corner piece 70 and forms in the erected carton a bellows corner. The panel 80, in the erected carton forms the end wall inner wall member and has a length somewhat less than that of the panel 79 and has its ends defined by cut lines 85 and 86 with said panel 80, as seen in Fig. 1, extending upwardly from the end 82 of panel 79 to a point short of the other end 82 of said panel 79. Between the upper ends 85 and 82, respectively of the panels 80 and 79, there is provided a tucking flap or tongue 87 hingedly carried by the panel 79 through the score or fold lines 77 beyond the panel 80. The panel 80 in addition has projecting from its sides short lugs 88 and 89 which as will later be made clear act as locking lugs for holding the carton, particularly the cover, in erected positions.

The panel 57 has its ends defined by similar score or fold lines 80 which respectively, integrally, hingedly connect to the said panel 57 the corner pieces 84. In order that the corner pieces 70 and 84 may be formed as a bellows corner they are each provided with a diagonal score or fold line 91.

After the blank has been cut and scored as above described adhesive 92 is applied to the upper surface of the panel or glue flap 50. Similarly, adhesive 93 is applied to the upper surface of the panel 41 while adhesive 94 is applied to the under surface of the panel 68. At this time the extension 35 is folded on the score or fold line 84 thereby bringing the adhesive 93 of panel 41 into engagement with the bottom or base supporting panel 30 whereupon reverse folds are effected successively on score or fold lines 43 and 38 thereby bringing the adhesive 92 on panel or glue flap 50 into engagement with the panel 57. At this time also the extension 68' is folded on score or fold line 82 thereby bringing the panel 75

or glue flap 68 into engagement with the cover panel 59, whereupon, pressure is applied to the folded blank effecting the definite adhesion of the parts to one another. The folded blank is now in its fully knocked-down position as illustrated in Fig. 2 and is shipped to the user in this condition.

The user upon desiring to set up the shipping and display box or carton raises the display base panel 36 from its superimposed position on supporting base panel 30 thereby arranging the panels 42 and 48 to be normal to the base 30 and with a flange 95 projecting forwardly of said base. The panels are retained in this position by first disposing the tucking flaps or ears 53 and 54 transversely of the bottom or base supporting panel 30 whereupon the flap 44 is bent to be normal to the panels 30 and 36 and the panel 47 tucked into the space between the said panels 30 and 36 to lie on the base panel 30 as clearly illustrated in Fig. 4.

The cover or lid is then assembled by raising the extension 68' from its flat or knocked-down position, illustrated at the upper end of Fig. 1, thereby arranging the panels 65 and 67 to be normal with the cover panel 59 with the panel 66 parallel with the said cover panel 59 and forming a bottom wall member for the cover front wall. At this time the cover end wall extensions 76 are successively, individually, raised from its flat extended position to dispose the panel 79 normal to the cover panel 59 and which panel 79 forms the cover end wall outer wall member. This raising of the extension 76 automatically, or at least permits, the inward folding of the corner pieces 70 and 84 on their diagonal score or fold lines 91 to form the bellows corners. The tucking flaps 75 and 56 are then arranged, or had previously been arranged, to extend transversely of the cover panel 59 whereupon the lug or tongue 87 is inserted beneath the adjacent end of the cover front wall bottom wall member or panel 63. At this time the panel 80, forming the end wall inner wall member is folded inwardly toward the end wall outer wall member or panel 79 until the locking lugs 88 and 89 snap behind the inset portions or shoulders 73-74 and 73'-74', respectively, of the cover front and back walls inner wall members or panels 67 and 58. The panel 81, at this time, acts as a creeper or locking flange and is superimposed on the cover panel 59.

The display box or carton is now as set up in Fig. 3. It will be noted that the base or bottom of the box or carton has a projecting flange 95 on which rests the cover flange front wall bottom wall member or panel 63 which thereby limits the movement of the cover and bottom relative to one another in a closing direction while the sides of the bottom are completely received between the end walls of the cover.

It will be noted in Fig. 1 that the cut and score lines which form the corresponding ends of the several panels are in alignment which results in the base of the display box or carton and especially the bottom or supporting base panel 30 being within the end walls of the cover or lid. In the modification disclosed in Figs. 5 to 8, inclusive, the bottom or supporting base panel 30' has its ends formed as score or fold lines 96 instead of cut lines 31 with said score or fold lines 96 outwardly of the score lines which form the panel's ends thereby giving to the bottom or supporting base panel 30' length in excess of the display base panel 30. This additional length affords a flange at the ends of the dis-

play base as will subsequently be made clear. The bottom or supporting base panel 30' has integrally hingedly connected to each of its ends through the score or fold line 96 a tab 97 longitudinally divided by a score or fold line 98 to form panels 99 and 100. The blank in Fig. 5 is further modified over that of Fig. 1 to the extent of eliminating from the cover front and back walls inner wall members the tucking flaps 75 and 56 and providing the said panels 50' and 67' with ends formed by cut lines, respectively, 101 and 102 and with said cut lines 101 and 102 inwardly spaced from the score or fold lines which form the ends of said cover front and back walls outer members or panels. The said offsetting of the cut lines 101 and 102 is to the same extent of the offsets 73 and 73' in the panels 67 and 50 with said cut lines 101 and 102 affording shoulders throughout their height for locking the end wall inner wall member in its operative position.

Additionally, the blank of Fig. 5 has eliminated therefrom the cover or lid glue flap 68 and the cover or lid front wall bottom wall or panel 66 wherefore a cover or lid is provided having its front wall of double thickness instead of a front wall of appreciable thickness including inner and outer spaced apart wall members. In the blank of Fig. 5 the cover or lid end wall extension 76' has eliminated from it the creeper flap 81 as well as the locking lugs 88 and 89 utilizing instead, as intimated above, the panel 80' as the inner end wall which is locked in operative position by engagement throughout its height behind the shoulder forming ends 101 and 102 of front and back walls inner wall members or panels 50' and 67'.

After the blank of Fig. 5 is cut and scored as above described the panel 50', the panel 41', and the panel 67' are each provided with adhesive, respectively, indicated by reference numerals 92, 93 and 103 whereupon the extensions of the blank are folded to cause the panel 67' to engage with the panel 65 and the panel 41' to engage the base supporting panel 30' while the panel 50' engages the panel 57 all of which are thereby adhesively secured in position to provide a blank as illustrated in Fig. 6 when in its knocked-down position.

The user upon desiring to utilize the carton of Figs. 5 to 8 inclusive, sets the same up in the same manner as above described in connection with the blank of Figs. 1 to 4, inclusive. In order to avoid an exposed raw edge at each end of the base supporting panel 30' the tabs 97 are folded onto the panel 30' whereby the panels 99 form the exposed surfaces of the end flanges of the supporting base.

It will be noted from Figs. 3 and 7 that the cover or lid of each of the modifications there disclosed has the back wall thereof, formed by panel 57 and glue flap 58, of the blank of Fig. 1, and the corresponding panel 57 and glue flap or panel 50' of Fig. 5, on the same plane as the bottom or supporting base panel 30 and 30' thereby elevating the display base or panel 36 above the front flange 95 and said back wall assembly. In the modification illustrated in Figs. 9 to 12, inclusive, the cover or lid is shown as having its back wall assembly in the plane of the display base or panel 36 which requires a slight rearrangement of the panels of the blanks of Figs. 1 and 5 as clearly illustrated in Fig. 9.

Specifically, Fig. 9 discloses the blank modi-

fied over those of Figs. 1 and 5 by having the spacer panel 48 shifted from a position between the display base or panel 36 and glue flap or panel 50 to a position between the bottom or supporting base panel 30-30' and the back wall outer wall member 57 whereby, said spacer panel 48 is hingedly connected to the bottom or supporting base panel 30-30' through the score and fold line 33 while the said spacer panel 48 is connected with the cover back wall 57 through a score or fold line 49. The rest of the blank is substantially identical with the blanks of Figs. 1 and 5.

After the blank has been cut and scored as just described and disclosed in said Fig. 9 adhesives 92 and 93 are respectively applied to the panels 50 and 41' and at the same time adhesive 103 is applied to the under surface of the panel 67'. The panel 67' is now folded on the score or fold line 63 to bring its adhesive into engagement with the panel 65. At this time also the cover forming extension is folded on the score or fold line 34 which brings the flange forming panel 41' into engagement with the bottom or supporting base panel 30-30' and, without any reverse folding as above described in connection with the blank of Fig. 1, brings the glue flap or panel 50 into engagement with the panel 57. The blank of Fig. 9 is now in the condition and position as illustrated in Fig. 10 for shipment to the user.

The user upon desiring to set up the carton follows substantially the same steps as above set forth in connection with the setting up of the blank of Fig. 1. Briefly, this setting up consists of actuating the base members about the score or fold lines 43, 38, 33 and superimposed score or fold lines 40 and 49' for thereby separating or spacing the bottom or supporting and display base or panels from one another whereupon the said panels are locked in their operative positions through the tucking flaps or ears 53 and 54 and the arrangement of the panels 46 and 47 of the flap 44 to be normal to one another. The lid or cover is then set up in the same manner as above described.

In modifications heretofore described the supporting base or panel 30-30' has been made to a dimension to project forwardly and/or laterally of the display base or panel 36 thereby providing an extending flange for engagement by the free edges of the cover or lid front and end walls to thereby limit the movement of these parts relative to one another. In the modification disclosed in Figs. 13 to 18, inclusive, means are provided inwardly of the cover or lid to engage the display base or panel and thereby limit this movement of the parts. This construction is accomplished by a slight modification in the blank of Figs. 1, 5 or 9 and which modification is shown in Fig. 13.

The modification of the blank of Fig. 13 over the blank of Fig. 1 consists in eliminating from the base assembly the flange forming panel 41 and forming the bottom or base supporting panel 30'' and the display base or panel 36'' of substantially the same area with the spacing panel 42 therebetween on one side and the spacing panel 48 on the other side and between the said display base or panel 36'' and the bottom or base supporting panel 30''.

The main modification of the blank of Fig. 13 consists in providing the end wall inner wall member or panel 80''' with a lug or flap 104 which is partially cut from the said panel 80''' along

cut lines 105, 106 and 107 the latter being on a portion of the score or fold line 78 between the panel 80' and the creeper panel 81 with said remaining portion of the score or fold line 78 being indicated by reference character 78''. The lug 104 is hingedly connected with the panel 80'' through a score or fold line 113. The lug 104 is substantially longitudinally divided by a score or fold line 108 thereby providing in the lug 104 a substantially rectangular panel 109 and a substantially isosceles trapezoid panel 110 with the fourth side of the isosceles trapezoid panel 110 formed by a score or fold line 111. The score or fold line 111 integrally hingedly connects with the panel 110 a flap 112 which, in the erected carton, as will presently be made clear, forms a spacer or supporting pillar for the lid abutment. The blank of Fig. 13 is further modified by having the cover front wall inner wall member or panel 67'' inwardly cut or offset as at 73'' thereby providing a space for the lug 104 in assembly and effecting the shoulder or abutment for the lid or cover.

After the blank of Fig. 13 has been cut and scored as just described it has applied to its glue flange or panel 50 the adhesive 92 and the cover front inner wall member 67'' likewise has the adhesive 103 attached to its under surface as seen in Fig. 13. The blank is then folded on the score or fold line 33 for thereby bringing the panel 50 into face engagement with the panel 57 for adhesive connection while the panel 67'' is folded on its score or fold line 62 for thereby bringing the said panel 67'' into face engagement with the cover front wall outer wall member or panel 65. The blank is now in its knocked-down condition as illustrated in Fig. 14 for shipment to the user who upon desiring to use the same erects the base and cover sections in substantially the same manner as above set forth in connection with the blanks of Figs. 1, 5 and 9.

In the erection of the blank of Fig. 13 and particularly in setting up the cover or lid portion each of the lugs 104 is slightly inwardly bent on its score or fold line 113 whereupon the isosceles trapezoid panel 110 is bent rearwardly on the score or fold line 108 after having had inwardly bent or folded the spacer flap 112. Upon the inward folding of the cover end wall inner wall member or panel 80''' the lug 104 snaps behind the shoulder 73'' of the cover front wall inner wall member or panel 67'' as clearly shown in Fig. 17. At this time the isosceles trapezoid panel 110 of the lug 104 is parallel with the cover panel 59 and is spaced from said cover panel by the panel 109 at its inner or long edge, defined by the score or fold line 108, and is spaced at its outer edge by the spacing lug 112.

By the construction just described a diagonal brace and abutment is provided as clearly illustrated in Figs. 15 and 17 which abutments, one at each corner of the cover or lid, engage the forward corners of the base assembly diagonally thereof as readily seen from Figs. 16 and 18.

While the modification illustrated in Figs. 13 to 18, inclusive, discloses the cover or lid as having its back wall in the plane of the bottom or supporting base panel 30'' it will be understood that the panels of Fig. 13 may be rearranged as disclosed in Fig. 9 so that the said cover or lid will have its back wall in the plane of the display panel 36'' and it is believed that this is obvious in view of the disclosure above.

In the modification illustrated in Figs. 19 to 23, inclusive, there is disclosed a shoulder inwardly of the lid or cover which engages the supporting

base assembly throughout its entire front edge requiring a relatively simple modification in the blank of Fig. 1 to obtain this result. The full length internal shoulder is obtained by supplying to the blank extension 63''' an additional panel 114 which is connected with the cover front wall outer wall member or panel 65 through the score or fold line 62' with said panel 114 connected with the front wall inner wall member or panel 67''' through the panel 66'', which corresponds to the front wall bottom wall member or panel 66 of Figs. 1 to 4, inclusive. The said connection being effected through a score or fold line 115 between the panel 66'' and the panel 114.

In the formation of the knocked-down carton from the blank of Fig. 19 the panel 114 has secured to its under surface adhesive 116 whereby it is secured to the upper end of the cover or lid front wall outer wall member or panel 65. It should be noted that the panels 114 and 67''' are of such widths or heights that together they equal the width or height of the front wall outer wall member or panel 65.

It will be understood that the modification of the extension 63''' as just described is applicable to the display box or carton of Fig. 3 and is not limited to the specific disclosure of the display box or carton in Figs. 21, 22 and 23 and which specific modification will now be described.

As seen in Figs. 22 and 23 the assembled display box or carton has the lower edges of the lid or cover end walls inclined as at 117. This inclination of the said carton end walls is effected through a relatively simple modification of the end wall extension 76 of Fig. 1 and which end wall extension is indicated in Fig. 19 by the reference numeral 76'''. As there shown use is made of end wall inner and outer panels 118 and 119 substantially longitudinally separated from one another by a score or fold line 120 with said end wall inner wall member or panel 118 connected with the cover or lid panel 59 through the score or fold line 60. The score or fold line 120 between the panels 118 and 119 is inclined thereby providing said panels with a triangular shaped area in which its one end defining score or fold line 83'' is shorter than its other end defining score or fold line 82'' and wherein the cut lines 86'' and 85'' forming the ends of panel 119 are likewise of dissimilar length. It will further be noted that the panel 119 is of less length at its free side than at its side formed by the score or fold line 120 thereby providing a lug 121 projecting from the longer portion of said panel 119.

The blank of Fig. 19 after being cut and scored as above described and illustrated and in addition to having the adhesive 116 supplied to its panel 114, has adhesive 94 applied to the panel or glue flap 68 as has adhesive 92 applied to the glue flap or panel 50. The blank of Fig. 19 is, as intimated above, folded on the score or fold line 62 to thereby bring the panel 114 into engagement with the front wall outer wall member or panel 65 and the glue flap or panel 68 into engagement with the cover or lid panel 59. At the same time the blank is folded on the score or fold line 34 for thereby bringing the panel or glue flap 50 into engagement with the cover back wall of panel 57. The knocked-down display box or carton is now in the condition illustrated in Fig. 20 for shipment to the user.

The user upon desiring to set up the knocked-down carton of Fig. 20 follows the same steps as above described in connection with the setting up of the knocked-down carton in Fig. 2. The

carton resulting from the blank of Fig. 19 and its knocked-down carton in Fig. 20 is as illustrated in Figs. 21, 22 and 23 having the lower ends of the end walls inclining from the rear or back wall of the cover to the lower end of the cover front wall. It will be noted that the cover back wall is in the plane of the display base or panel 36 and that the said inclination 117 is from the point of joinder of the cover back wall with the base assembly to the lower or free end 10 of the cover front wall.

The modification illustrated in Figs. 24 to 28, inclusive, is substantially identical with that disclosed in Figs. 19 to 23, inclusive, except that the panels of the blank of Fig. 19 are rearranged to 15 correspond with the placement of similar panels in Fig. 1 thereby bringing the cover back wall, when open, in the plane of the display base supporting panel 30 similar to that disclosed in Fig. 3. The only modification in the blank of Fig. 24 over the disclosure in Fig. 19 consists in oppositely inclining the end wall extensions score or fold lines 120' thereby making the shorter ends of the end walls outer wall members or panels 118' and the similar ends of the end walls inner wall members or panels 119' at the upper end of the blank instead of at the lower end.

By this construction there is provided a display carton or box as illustrated in Fig. 28 wherein the inclination of the said cover end walls lower ends 117' is from the front to the back instead of from the back to the front as illustrated in Fig. 23. By this construction, also, the front edge of the assembled base or the base panels spacing panel 42 has its outer surface exposed as well as having the outer corners of the base assembly free and exposed. By this construction the said base assembly, through the exposed side wall lower corners, may be grasped between the fingers of one hand and the cover or lid assembly grasped by the other hand for raising or opening the same.

It is frequently desirable to print the inner surface of the cover panel 59 which, with the blanks heretofore described, would require printing on both sides of the blank and assuming that the exterior of the carton is to be printed, which is the practice. By printing is here meant either carton content description, ornamentation, covering with an additional layer of material or some other decoration which is applied to the blank either before it is cut and scored or thereafter. With the blanks heretofore described this second printing on the normal under surface of the cover panel would be expensive while with the addition to the original blank of a small amount of box board or other carton material this printing can be done in one operation and on the same side of the blank.

The blank of Fig. 29 is designed for this purpose and merely requires the formation of the glue flap 68 of the blank of Fig. 19 of an area to cover the lid or cover panel 59 between the point of attachment of the cover or lid front wall inner wall member to the bounding score or fold line 58. This flap is indicated in Figs. 29 to 33, inclusive, by the reference character 68'. It will be understood that when the blank of Fig. 29 is first formed and scored that the extension including the same is in the same plane as the rest of the blank as illustrated in Fig. 29 wherefore the printing of the underside of said blank, as illustrated in Fig. 29, will include the printing of the flap or panel 68' so that when it is secured in its

operative position, as illustrated in Figs. 29, 31 and 32, the said printing is exposed to view.

It will be understood that this flap 68' may be incorporated with the blanks of Figs. 1, 5, 9 and 13 to obtain the same results of a printed inner surface on the cover or lid.

This same result of a printed inner lid or cover panel is obtained from the blank of Fig. 35 which has eliminated therefrom the panel or flap 68' and instead has added thereto a flap or panel 122 connected with a glue flap or cover back wall inner wall member 50 through a score or fold line 123 which in the erected carton is in superimposed alignment with the cover panel bounding score or fold line 58.

It will be readily appreciated that with the blank of Fig. 39 in its fully extended position and the printing thereof on the under side, as seen in said Fig. 35, that the flap or panel 122 can be 20 readily printed so that when in its erected position, as in Figs. 37 and 38, the printing is readily legible. After the blank has been cut and scored 25 the flap or panel 122 has adhesive 124 applied thereto at the time the adhesive 92 is being applied to the panel 50.

It will be understood that the flap 122 may be incorporated with the blanks of Figs. 1, 5, 9, 13 and 19 in obtaining the same result.

The display panel 36 in Fig. 35 is shown as having formed therein a cut-out portion 125 for the purpose of receiving an article to be supported and displayed by the display box or carton. This cut-out portion 125 may take any contour depending upon the article to be displayed and it is to be understood that the corresponding display base or panel of each of the other blanks disclosed in this application may be correspondingly designed or arranged.

From the foregoing it is believed now evident 40 that there has been provided a construction which answers the objects initially set forth.

What is claimed is:

1. In a display box or carton formed from a single blank cut and scored to form a base portion and a cover portion hingedly connected to one another through a hinge fold line, said base portion including a base supported panel, an upwardly spaced goods supporting and display panel and connecting members normal to said base supporting and goods supporting and display panels between the front and back edges thereof, said cover portion comprising a cover panel with front, back and end walls projecting therefrom toward the base portion, said goods supporting and display panel and covering panel being of substantially equal area and said goods supporting and display panel being adapted to be embraced by the cover walls, means on one of said cover and base portions connectable to the other beyond the hinge line for reinforcing the hinge between the base portion and cover portion, and means carried by the base and cover for engagement to limit the closing of the cover on the base, comprising a shoulder inwardly projecting from one of the cover walls for engagement with the goods supporting and display panel.

2. In a display box or carton formed from a single blank cut and scored to form a base portion and a cover portion hingedly connected to one another through a hinge fold line, said base portion including a base supporting panel, an upwardly spaced goods supporting and display panel and connecting members normal to said base supporting and goods supporting and display panels between the front and back edges

thereof, said cover portion comprising a cover panel with front, back and end walls projecting therefrom toward the base portion, said goods supporting and display panel and covering panel being of substantially equal area and said goods supporting and display panel being adapted to be embraced by the cover walls, means on one of said cover and base portions connectable to the other beyond the hinge line for reinforcing the hinge between the base portion and cover portion, and means carried by the base and cover for engagement to limit the closing of the cover on the base, comprising in the blank panels integrally, hingedly connected with the cover front wall foldable at right angles to one another and secured in position forming a shoulder inwardly of the front wall and extending the full length thereof for engagement with the goods supporting and display panel.

3. In a display box or carton formed from a single blank cut and scored to form a base portion and a cover portion hingedly connected to one another through a hinge fold line, said base portion including a base supporting panel, an upwardly spaced goods supporting and display panel and connecting members normal to said base supporting and goods supporting and display panels between the front and back edges thereof, said cover portion comprising a cover panel with front, back and end walls projecting therefrom toward the base portion, said goods supporting and display panel and covering panel being of substantially equal area and said goods supporting and display panel being adapted to be embraced by the cover walls, means on one of said cover and base portions connectable to the other beyond the hinge line for reinforcing the hinge between the base portion and cover portion, and means carried by the base and cover for engagement to limit the closing of the cover on the base, comprising a shoulder formed from certain of the cover end and front walls cooperating with the other of said end and front walls to form shoulders disposed diagonally of the cover front corners interiorly thereof for engagement with the goods supporting and display panel.

4. In a display box or carton formed from a single blank having a base forming portion and a cover forming portion hingedly connected to one another through a hinge fold line, said base forming portion including a base supporting panel, an upwardly spaced goods supporting and display panel, spacing and connecting panels substantially normal to and at each edge of the base supporting and goods supporting and display panels to space said base supporting panel and goods supporting and display panel from one another and means for locking said panels in said positions, said cover forming portion including a cover panel of an area substantially equal to the area of the goods supporting and display panel, said covering panel having extensions from the sides thereof foldable to form a front wall of inner and outer wall members, end walls of inner and outer wall members, a back wall, and cooperating means on said cover front and end walls inner and outer wall members and back wall for locking the same in erected positions, said base forming portion of the blank including a glue flap for attachment to the cover back wall for reinforcing the hinge connection between the cover and base, and means associated with said base forming portion of the blank and the cover forming portion of the blank for engagement with the other for limiting the closing of the cover,

comprising in the blank panels integrally, hingedly connected with the cover front wall foldable at right angles to one another and secured in position forming an inwardly projecting shoulder on said cover front wall inner wall member for engagement with the goods supporting and display panel at the forward edge thereof.

5. In a display box or carton formed from a single blank having a base forming portion and a cover forming portion hingedly connected to one another through a hinge fold line, said base forming portion including a base supporting panel, an upwardly spaced goods supporting and display panel, spacing and connecting panels substantially normal to and at each edge of the base supporting and goods supporting and display panels to space said base supporting panel and goods supporting and display panel from one another and means for locking said panels in said positions, said cover forming portion including a cover panel of an area substantially equal to the area of the goods supporting and display panel, said covering panel having extensions from the sides thereof foldable to form a front wall of inner and outer wall members, end walls of inner and outer wall members, a back wall and cooperating means on said cover front and end walls inner and outer wall members and back wall for locking the same in erected positions, said base forming portion of the blank including a glue flap for attachment to the cover back wall for reinforcing the hinge connection between the cover and base, and means associated with said base forming portion of the blank for engagement with the other for limiting the closing of the cover, comprising a lug integral with each cover end wall inner wall member inwardly of the ends thereof adjacent the front wall for disposal angularly thereto toward the said front wall, and means for anchoring the said lugs to the front wall in their angular position.

6. In a display box or carton formed from a single blank having a base forming portion and a cover forming portion hingedly connected to one another through a hinge fold line, said base forming portion including a base supporting panel, an upwardly spaced goods supporting and display panel, spacing and connecting panels substantially normal to and at each edge of the base supporting and goods supporting and display panels to space said base supporting panel and goods supporting and display panel from one another and means for locking said panels in said positions, said cover forming portion including a cover panel of an area substantially equal to the area of the goods supporting and display panel, said covering panel having extensions from the sides thereof foldable to form a front wall of inner and outer wall members, end walls of inner and outer wall members, a back wall and cooperating means on said cover front and end walls inner and outer wall members and back wall for locking the same in erected positions, said base forming portion of the blank including a glue flap for attachment to the cover back wall for reinforcing the hinge connection between the cover and base, and means associated with said base forming portion of the blank for engagement with the other for limiting the closing of the cover, said cover end walls inner and outer wall members being substantially wedge shaped with the smaller dimension of each wall member of its end wall adjacent one another whereby the lower

edge of said cover end walls incline with respect to the plane of extent of the base supporting and goods supporting and display panels.

7. In a display box or carton formed from a single blank cut and scored to form a base portion and a cover portion hingedly connected to one another through a hinge fold line, said base portion including a base supporting panel, an upwardly spaced goods supporting and display panel and connecting members normal to said base supporting and goods supporting and display panels between the front and back edges thereof, said cover portion comprising a cover panel with front, back and end walls projecting therefrom toward the base portion, said goods supporting and display panel and covering panel being of substantially equal area and said goods supporting and display panel being adapted to be embraced by the cover walls, means on one of said cover and base portions connectable to the other beyond the hinge line for reinforcing the hinge between the base portion and cover portion, one of said base portion and cover portion having a flap superimposed on the cover panel for exposing the side of the blank normally exposed by said base portion and cover portion, and cooperating means on said base portion and cover portion for limiting the closing of the cover onto the base portion.

8. In a display box or carton formed from a single blank cut and scored to form a base portion and a cover portion hingedly connected to one another through a hinge fold line, said base portion including a base supporting panel, an upwardly spaced goods supporting and display panel and connecting members normal to said base supporting and goods supporting and display panels between the front and back edges thereof, said cover portion comprising a cover panel with front, back and end walls projecting therefrom toward the base portion, said goods supporting and display panel and covering panel being of substantially equal area and said goods supporting and display panel being adapted to be embraced by the cover walls, means on one of said cover and base portions connectable to the other beyond the hinge line for reinforcing the hinge between the base portion and cover portion, a flap integral with said base portion superimposed on the cover panel for exposing the side

of the blank normally exposed by said base portion and cover portion, and means carried by the base portion and cover for engagement to limit the closing of the cover on the base.

- 5 9. In a display box or carton formed from a single blank cut and scored to form a base portion and a cover portion hingedly connected to one another through a hinge fold line, said base portion including a base supporting panel, an upwardly spaced goods supporting and display panel and connecting members normal to said base supporting and goods supporting and display panels between the front and back edges thereof, said cover portion comprising a cover panel with front, back and end walls projecting therefrom toward the base portion, said goods supporting and display panel and covering panel being of substantially equal area and said goods supporting and display panel being adapted to be embraced by the cover walls, means on one of said cover and base portions connectable to the other beyond the hinge line for reinforcing the hinge between the base portion and cover portion, one of said base portion and cover portion having a flap integral with said cover portion superimposed on the cover panel for exposing the side of the blank normally exposed by said base portion and cover portion, and means carried by the base portion and cover portion for engagement to limit the closing of the cover on the base.
